UNITED STATES PATENT OFFICE.

FREDERICK BAKER, OF CAULFIELD, VICTORIA.

SPIKE.

SPECIFICATION forming part of Letters Patent No. 621,737, dated March 21, 1899.

Application filed December 13, 1898. Serial No. 699,147. (No model.)

To all whom it may concern:

Be it known that I, FREDERICK BAKER, builder, a subject of the Queen of Great Britain, residing at Maylands, Kambrook road, 5 Caulfield, near Melbourne, in the British Colony of Victoria, have invented an Improved Spike for Securing Rails, Decking, Platforms, and the Like, (for which I applied for a patent in Victoria, application filed August 16, 1898, 10 and numbered 15,451; in New South Wales, application filed August 19, 1898, and numbered 8,590; in South Australia, application filed August 18, 1898, and numbered 5,534; in Queensland, application filed August 20, 1898, 15 and numbered 4,528; in Tasmania, application filed August 22, 1898, and numbered 2,246; in New Zealand, application filed August 29, 1898, and numbered 10,919; in Western Australia, application filed August 23, 1898, and 20 numbered 2,183, and that in addition an application for Letters Patent in Great Britain was sent from Melbourne aforesaid on the 16th of August, 1898, but that I do not know the actual date of filing of such application nor its 25 number,) of which the following is a specification.

This invention relates mainly to the spikes used on railways for securing the flanges of the rails to the sleepers, but it is also applicable for numerous other purposes where spikes or studs are employed—as, for instance, in securing decking and platforms to joists.

The main object of the invention is to provide a spike or stud which will securely hold 35 rails, planking, and the like without working loose, but which can be removed and replaced at will.

In order that my invention may be easily understood, I will describe it by reference to 40 the accompanying drawings, in which—

Figure 1 is a side elevation of a spike such as would be used on railways for securing the rails to the sleepers, showing same constructed in accordance with this invention. Fig. 2 is 45 a plan of said spike; and Figs. 3 and 4 are transverse sections on lines 3 3 and 4 4, respectively, of Fig. 1. Fig. 5 is a side elevation of a spike or stud adapted to be fitted into a countersunk hole for securing plank- 50 ing or the like to joists, for instance. Fig. 6 is a sectional elevation illustrating the application of my invention to a hook - and - eye

gate-hinge. Fig. 7 is a similar view to Fig. 3, illustrating a slight modification which can be made in the construction of the spike, as here- 55 inafter described. Fig. 8 is a sectional elevation illustrating a further modification which might be made in my improved spike to adapt it more particularly to railway-work.

The same letters of reference indicate the 60 same or corresponding parts in all the figures.

According to this invention the spike or stud is made in two parts A and B; the latter of which is formed with one to three 65 projecting teeth C, as shown, while the former is wedge-shaped for a portion of its length and is adapted to be driven into the hole behind the part B, so as to drive the teeth C forward into the body of the sleeper, joist, or the like.

If intended for securing rails to sleepers, the part B of the spike may have a projecting head D to engage the flange of the sleeper, and at its lowest end it has a projection E, preferably slightly inclined on its upper edge 70 and adapted to be forced into engagement with the under side of the sleeper. The lower end of the part B of the spike is preferably grooved out for a short distance, as indicated at F, by which means the spike is made lighter 75 and a certain saving of metal is effected.

The part A of the spike is formed with a slightly-projecting head G to facilitate its withdrawal, and it can be made square for a certain portion of its length—say down to 80 about the part marked H—the remainder of its length being curved or rounded, as in Fig. 4. The face bearing against the part B of the spike may be curved slightly to correspond to a similar curve which may be made 85 on said part B, as illustrated at I in Fig. 3.

The shank of the spike may be square instead of oval or round; but by preference it is constructed of the section shown in Figs. 3 and 4.

The corners K of the part B are rounded off, as shown, to enable said part B to be moved back into the hole when the part A has been removed. The corners L of said part A are made so as to project slightly, so 90 that by being embedded in the timber they will assist in preventing the spike turning around, and thus becoming disengaged from the flange of the rail.

The spike or stud illustrated in Fig. 5 is substantially the same as shown in Fig. 1, except that the head is shaped to fit into a countersunk hole, so as to be flush with the surface of decking, planking, or other timbers, this construction being useful for securing the planking or decking of platforms and the like, and owing to the hold the three teeth C would have in the joists it cannot be drawn out by the warping of the decking, and, moreover, can be fixed in much less time than screws.

The application of the invention for other purposes—as, for instance, for securing hook-and-eye hinges to gates and gate-posts—will be readily understood from Fig. 6, the part B, carrying the hook, being held in a hole in the gate-post by the three teeth C, with which it is provided, being driven into the post on the insertion of the part A. The other part of the gate-hinge could be secured to the gate in the ordinary manner; but instead of using screws small spikes of the kind illustrated in Fig. 5 could be employed.

In order to compensate for shrinkage in the sleepers, my improved spike might be constructed, as illustrated in Fig. 8, with a slot through its upper end, through which a tapering or inclined key M might be passed, the rear end of said key being formed with teeth N to engage with the surface of the sleeper and so prevent the key working loose. By driving this key in farther it will tighten its hold on the rail and draw the projection E on the lower end of the spike against the under side of the sleeper, thus compensating for any shrinkage of this latter.

Having now particularly described and ascertained the nature of my said invention and in what manner the same is to be performed, I declare that what I claim is—

1. A spike for securing rails to sleepers and other like purposes, consisting of two parts, one having teeth projecting from one side at right angles to the longitudinal line of said part, and the other part being plain and adapted to be driven down behind the first part to force said teeth into the wood, the second part being wider than the first and having a concave face against which the convex face of the narrower toothed part has bearing, substantially as described. 45

2. A spike for securing railway-rails to sleepers and for other like purposes, consisting of two parts, the first part having at top and bottom a head and a foot projection at right angles to its longitudinal line and teeth between said points projecting in the same direction, and a second part adapted to be driven in against the opposite parallel face 60 of said first part, the second part being of greater width than the first, so as to project beyond the sides, or edges, of the latter and prevent the spike from turning, substantially as described. 65

3. A spike for securing railway-rails to sleepers and other like purposes, consisting of two parts, the first part being provided with projections at its ends and with teeth intermediate the same projecting on one side 70 at right angles with the longitudinal line of said part, the second part being adapted to bear against an opposite, plain convex face of the first part to force said teeth into the wood, said second part being wider than the 75 first and having a concave face against which the plain convex face of the first part has bearing, substantially as described.

FREDERICK BAKER.
